UNITED STATES PATENT OFFICE

JOHN S. HOFFMIRE, OF AUBURN, NEW YORK

SHOE RACK

Application filed May 14, 1928. Serial No. 277,697.

This invention relates to certain improvements in shoe racks; and the nature and objects of the invention will be readily recognized and understood by those skilled in the arts involved in the light of the following explanation and detailed description of the accompanying drawings illustrating what I at present consider to be the preferred embodiments or mechanical expressions of my invention from among various other forms, arrangements, combinations, and constructions of which the invention is capable within the spirit and the scope thereof.

Shoe racks of the type with which the present invention deals are employed in shoe factories for transporting shoes from one place or machine and shoe making operation to another and for holding unfinished shoes between operations in the process of manufacturing shoes, as well as for transporting the finished shoe to and for storing or holding the same at the point of packing for shipment. Such shoe racks are generally characterized by rows of spaced pins or paddles on and between which the shoes are supported and held so as to be out of contact or engagement with each other, the rows of pins or paddles providing a series of horizontally disposed and vertically spaced shelves in each rack.

Certain serious problems and difficulties are presented to the shoe manufacturer by these shoe racks. Among the major problems may be mentioned the following; the large amount of space required in a factory by the racks due to the number thereof necessary to handle the shoes going through the process of manufacture and to hold and store the finished shoes, and the further fact that different types of racks are frequently used in the handling of shoes at different stages in the process of manufacture; the initial cost of the racks and the cost of repairs and replacements resulting from breakage of the racks in use; the loss of shoes damaged through improper contact or engagement with portions and unprotected parts of the racks and through contact or striking with other racks or structures adjacent thereto or in collision therewith; and in the re-

tarding or slowing up of production, as well as the lowering of the quality and workmanship of the shoes, resulting from the difficulty encountered by the operators in removing the proper shoes from and in replacing the shoes in their proper positions on the racks, in the performing of the necessary shoe making operations on the shoes as they pass through the factory on the racks from operation to operation.

The desirability of sending shoes through the process of manufacture in pairs and of maintaining the shoes of a pair together through the various steps, has been established, particularly for the higher grades of shoes. But experience has shown that with the racks now in use in shoe factories, and under the methods of racking and arranging the shoes as practiced and permitted by the designs of such racks, the racking of shoes in pairs causes considerable confusion and loss of time on the part of operators in selecting the proper shoes from the racks and in replacing the shoes operated on so as to maintain the shoes of a pair together, with the resulting increase in mismatched and unmatched pairs of shoes. A further difficulty arises with these shoe racks in endeavoring to maintain the length and width thereof to a minimum, while providing for the desired racking arrangement of the shoes, size of the racks being a vital consideration because of the large numbers required by a factory so that any saving in length or width on each rack means a large factory space saving in the aggregate, as will be readily recognized by anyone familiar with shoe racks and their operation and use.

A main characteristic and object of the present invention resides in a design, arrangement and construction of shoe rack on which the shoes can be racked and arranged in such a manner as to render it particularly easy for the operators to remove and replace the same for work thereon without confusion or loss of time, and to permit of keeping the shoes in pairs throughout the process of manufacture without mismatching or mixing the shoes of a pair, while retain-

ing in and for the rack that essential and highly important requirement for minimum length and width of rack, all to the end of eliminating the mentioned problems and difficulties and materially speeding up the production of the shoes.

A further characteristic of the invention is found in the design and arrangement of the shoe supporting pins or paddles forming the rack shelves, by which alternate shelves are designed to support either all right shoes or all left shoes, so that the shoes are racked and supported in pairs with the shoes of each pair vertically spaced and positioned one above the other, thus enabling an operator to set a machine for work on lefts or on rights and complete the operation on all the shoes of one shelf before changing over the machine, while being enabled to readily return the shoes to proper places in the rack maintained in pairs; and further to so design and mount the paddles or pins of each shelf that the shoes are supported out of contact, but the shelf can be made of a minimum length to thereby permit the production of a rack of smaller dimensions to occupy a minimum of factory space in use.

Shoe racks in use in a factory are subjected to hard usage occasioned by frequent collisions between racks, with adjacent structures and machines, and through handling in moving them from place to place, yet the shoes supported thereon must be protected not only from engagement with adjacent structures but with damaging portions of the rack itself, to maintain loss from ruined shoes to a minimum. A further aim and object of the invention is the provision of a rack which is of simple relatively inexpensive construction but which is durable in use with a minimum possibility of breakage; which provides protection at all times for the shoes from adjacent structures, and is so designed that in placing shoes thereon and removing them therefrom, the shoes cannot come in contact with portions of the rack structure capable of injuring them; and further to provide such a rack which is of relatively light weight and so designed as to be readily handled in pushing the same from place to place.

Another object of the invention is to provide a design and construction of shoe rack in which the main frame is formed of metal and requires a small number of parts of minimum weight and quantity of material, yet which retains the necessary strength and rigidity to withstand the conditions encountered in use; and further to provide such a frame with a construction and mounting of wooden or the like material shoe retaining and supporting members or paddles which will be strong and rigid with a minimum possibility of breakage in use, and all

so arranged and mounted on the metal frame as to eliminate the possibility of the shoes being injured by contact or engagement with the metal structure in placing shoes in and removing them from the rack.

Another object of the invention is to eliminate the necessity in a shoe factory for different types of racks for transporting unfinished shoes through the process of manufacture, and for holding and transporting finished shoes, through the provision of an all-purpose shoe rack adapted for holding unfinished shoes in the required positions, as well as for holding the finished shoes in the desired sole downward positions.

With the foregoing general objects and characteristics in view, as well as certain others which will be readily apparent from the following description, the invention consists in certain novel features in construction and in the combinations and arrangements of the parts and elements of the shoe racks, as will be more fully and particularly referred to and specified hereinafter.

Referring to the accompanying drawings, in which similar reference characters refer to corresponding parts throughout the several figures thereof:

Fig. 1, is a perspective view of a shoe rack embodying the several features of the invention, and showing several pairs of shoes in different positions supported thereon and therein, in accordance with the invention.

Fig. 2, is a top plan view of the shoe supporting paddles forming a shelf of the rack for receiving and supporting right shoes, portions of the metal rack frame being shown in horizontal section.

Fig. 3, is a view of a portion of the shoe rack showing portions of adjacent shelves, one in vertical section and the other in front elevation.

Fig. 4, is a view of adjacent shelves and portions of the rack frame in end elevation showing shoes in different positions thereon, portions of the frame and shelf mounting being broken away and shown in vertical section.

A shoe rack of the twelve pair, flat pin or paddle type, embodying the features of design, arrangement, and construction of the invention, is disclosed in the accompanying drawings and described herein purely by way of example and not of limitation, for the purpose of explaining the invention to enable those skilled in the art to understand the same. The several features of the invention are not restricted to the particular type or capacity of shoe rack shown, or limited to the specific mechanical expressions thereof, but are of general adaptation and use to and in shoe racks of various other types, and the invention contemplates and includes such other adaptations and forms, it being understood that the pres-

ent disclosure is to be so interpreted and read.

In the illustrated example, referring now to Fig. 1, of the drawings in particular, the shoe rack includes a main frame of metal, preferably of the angle iron type, which consists of the base 10 and the vertical end members or posts 11 extending upwardly therefrom at opposite ends and adjacent one side (the rear) thereof. The base 10 of the rack frame is, in the example hereof rectangular in form and consists of the opposite side bars 12 and end bars 14 of angle cross section, suitably bolted or otherwise secured together with their horizontal flanges faced inwardly toward each other and their vertical flanges forming a rim or wall around the base 10. Suitable diagonal corner braces 15 connect bars 12 and 14, while a series of bottom forming rods or strips 16 are secured spaced apart and extending across and between the horizontal flanges of the side bars 12 to provide an article receiving and supporting bottom for the base 10, as will be clear by reference to Fig. 1 of the drawings. The frame base 10, so formed and constructed is provided with the usual or any suitable casters or the like 17 supporting the base and by which the rack can be readily rolled and steered from place to place, in the usual manner.

In accordance with a feature of the invention, the vertical end members or posts 11 are bolted or otherwise secured to and on the opposite end bars 14 of base 10, respectively, adjacent one side bar 12 (the rear bar) thereof, so that these vertical members extend upwardly from opposite ends and at one side (the rear) of the frame base, thus leaving the space upwardly from the major portion of the base, and forwardly from members 11, unobstructed thereby. Each of the vertical frame end members or posts 11, is formed of a metal angle bar but with the flange 18 thereof, of a greater width than the flange 19. The vertical members or posts 11, of such angle form, are bolted at their lower ends through the wide flange 18 to the inner sides of the vertical flanges of the opposite end bar 14, of base 10, with the posts 11 resting on the horizontal flanges of these end bars and the wide flanges 18 extending forwardly of the base substantially parallel with end bars 14, while the narrow flanges 19, extend inwardly toward each other along the adjacent side or rear bar 12 of base 10. These vertical frame members or posts 11, are braced at their lower ends by the diagonal braces 11', extending forwardly to the base end bars 14, and inwardly to the adjacent rear side bar 12. The main frame of metal for the rack, thus provides the base 10, and the substantially parallel, and spaced opposite end members or posts 11, rigidly braced

and secured thereon extending upwardly from and along one side of the base and the wide flanges 18 of which strengthen the same in the necessary direction, as clearly illustrated by Fig. 1 of the drawings.

The vertical frame members or posts 11 have the shoe supporting shelves disposed horizontally therebetween and supported and secured thereon, and in the particular example of the invention here disclosed, each member or post 11, has a series of vertically spaced shelf or paddle receiving and supporting brackets 20 secured thereon and horizontally disposed extending forwardly therefrom. The brackets 20 are inclined upwardly and forwardly from posts 11, and the brackets of each post are in horizontal alinement with the corresponding brackets of the other post. Each bracket 20 is in this instance formed of a metal angle member having the flanges 21 and 22, referring now to Figs. 2, 3 and 4 of the drawings in particular, and is secured to and extending transversely of and forwardly from the wide flange 18 of a side member or post 11, by the bolts 23 through the vertical flange 21 of the bracket and post flange 18. In secured position the flange 22 of each bracket is horizontally disposed and extends inwardly from the post 11. In order to strengthen and brace the vertical frame members or posts 11, and further to provide in effect a guard along the inner side of each shoe supporting shelf structure, a wooden cross rail and brace 24, is bolted across and between the posts 11 at the rear or outer side of flanges 19 thereof, by the bolts 24' extending therethrough, disposed horizontally and above the inner ends of each of the horizontally alined pairs of the supporting brackets 20 (see Fig. 1).

The type of shoe rack here disclosed as an example, is designed to receive and support twelve pairs of shoes, and four pairs of the brackets 20 are provided on the frame end posts 11, for mounting and supporting four shoe supporting shelf structures vertically spaced and horizontally disposed extending between and across these frame end members or posts 11. Each shelf structure includes a paddle bar 25, preferably as in the present instance formed of a suitable wood, of a generally rectangular cross section, although not so limited, extending between a pair of the brackets 20 with the ends thereof secured to and against the under sides of the horizontal flanges 22 of the brackets and rigidly bolted thereto by means of the spaced bolts 26 extending therethrough. The paddle bars 25 are thus bolted to and disposed beneath brackets 20, with the upper side of each bar disposed at an upward and outward inclination and in the horizontal plane of the upper sides of the flanges 22 to which they are respectively bolted. In the pres-

ent example, the upper sides of the paddle bar ends are recessed to receive the bracket flanges 22 and dispose the upper surface of each bar between the brackets flush with the 5 upper faces of the bracket flanges 22, as clearly shown by Fig. 3 of the drawings in particular.

On each paddle bar 25 and its supporting brackets 20, a series of spaced intermediate 10 shoe supporting paddles 27 and end paddles 28, all formed of wood or other material which will not damage shoes in contact therewith, are mounted between the frame end posts 11 and extended outwardly and 15 forwardly from and transversely of the bars 25. These shoe supporting paddles 27 and 28 are formed of an elongated generally rectangular form, and the end paddles 28 are of a considerably less width than paddles 27, 20 for a purpose referred to hereinafter. The end paddles 28 of each shelf structure are mounted with their outer side portions received and supported on the brackets 20, respectively, with the horizontal flanges 22 supporting the same and the outer edges of the paddles against the vertical flanges 21 of the brackets (see Figs. 2 and 3). The inner or base ends of the end paddles 28 are secured to the brackets and the paddle bar 25, by the bolts 26, which are extended upwardly therethrough. The outer end lengths of paddles 28 are secured to the bracket vertical flanges 21 by means of screws or the like 29, so that these end paddles are 30 securely and rigidly fastened in position on and supported by the brackets 20 and the 35 paddle bar 25.

The intermediate paddles 27 are secured on and to each paddle bar 25 between the 40 end paddles 28, spaced therefrom and from each other to provide the shoe receiving spaces 30 therebetween, by the bolts 31 extended through the base ends of the paddles and bar 25, and the screws 32 (see Fig. 2) 45 extended downwardly therethrough into the paddle bar 25. In order to provide a substantially smooth, and continuous surface over and along the base ends of paddles 27 and 28, filler blocks 33 are secured by screws 50 or the like onto the bar 25 in the spaces between the paddles, which filler blocks are of a width not exceeding that of the bar 25. Thus, each shelf structure provides and 55 includes the series of spaced shoe receiving and supporting paddles 27 and 28 fixed to and extending forwardly from the paddle bar 25 over and above the frame base 10, but of a length not to extend beyond the base, and given an upward and forward or outer in- 60 clination by the bar 25 and brackets 20, on the frame end posts 11.

Each vertically aligned series of end paddles 28 and brackets 20, carried by a frame end member 11, is provided with a vertically disposed rod or dowel member 34, preferably

of wood, extending upwardly therethrough to and a distance above the upper end paddle, the rod extending through the paddles and the horizontal flanges 22 of brackets 20, adjacent the outer free ends of such flanges, 70 as will be clear by reference to Figs. 1 and 4. These end paddle connecting rods 34 additionally brace and strengthen the end paddles and brackets, and serve to prevent displacement of the shoes from the rack under 75 certain positions of shoe mounting, as well as performing certain other functions hereinafter referred to.

A movable and adjustable toe supporting bar or rest 35, is normally supported on and across the inner ends of the paddles 27 and 28 of each shelf structure, between and confined against longitudinal displacement by the vertical flanges 21 of the brackets 20 (see Fig. 2). Wooden or the like material blocks 36 are fixed over the base ends of each end paddle 28 to cover and protect the projecting ends of bolts 26, and provide stops or abutments against which the ends of the toe rests bear and by which these rests are positioned. The toe rests 35 are preferably rounded on their upper sides and if desired can be covered with a suitable soft or protective covering, and provide a support for the toes of shoes supported between the paddles with their soles upward, as will be later explained. These toe rests 35 are removable from the normal position above described, to a position across the outer end lengths of the shoe supporting 100 paddles forward of and positioned against the vertical rods 34, as shown by the bottom shelf structure in Figs. 1 and 4. In this position rests 35 serve to retain shoes in proper position on the paddles sole downward, while the rods 34 serve the additional purpose of preventing displacement of shoes so supported endwise of the shelf structure, as well as protecting the end shoes from contact with objects adjacent the ends of the rack. 110

In accordance with a main and basic feature and principle of the invention, the shoe supporting paddles 27-28, are designed, constructed and mounted to permit the racking of all and only right shoes or all left 115 shoes on each shelf structure, and to arrange the adjacent shelf structures to co-operate in enabling the racking of shoes in pairs so that operators can maintain the shoes of a pair together throughout the process of manufacture. The shoe supporting paddles 27-28 of each shelf structure are beveled or rounded at 27^a (see Fig. 2) on their adjacent and facing edges, and are formed of a minimum width and spacing to 120 permit of supporting shoes, such as R and L in Fig. 1, therebetween with their soles upward, but adjacent shoes out of contact. The paddles 27-28 of shelf are formed with one edge thereof concaved as at 27^b in the 130

upper shelf paddles of Fig. 2, while the adjacent and opposite paddle edge is formed straight. This construction of the paddles provides for receiving a shoe in the space 5 30 and the concavity 27^b between adjacent paddles and conforms to the shape of the shoe so as to cradle and hold the same in proper position against displacement.

With the upper shelf of the rack, referring to Fig. 2, the paddles thereof each have 10 their right hand edge concaved (when facing the rack from the front thereof) and due to the minimum spacing, such construction and arrangement will permit of receiving only right shoes R between the paddles, 15 due to the shape of such shoes, as will be readily understood. Now, the shelf structure next below the top shelf structure of the rack, has the paddles 27-28 each concaved at 27^c, along the opposite edges of the 20 paddles with respect to the concavities 27^b of the paddles next thereabove, so that the paddles having concavities 27^c will only receive and rack left shoes L. Thus, 25 considering the two upper shelf structures, the top one thereof racks all right shoes and the lower one all left shoes, with the right and left shoes, R and L, of each pair arranged on the rack in vertical alinement one 30 above the other. This enables the operators to first perform the operations on all the right shoes along the top row without changing the machine, and then perform the operations on the left shoes, or vice versa, 35 and to remove and replace the shoes in their proper positions to keep the pairs together with difficulty or confusion and in a minimum of time.

In the rack of the present example, the 40 four shelf structures have the paddles 27-28 thereof arranged alternately for right shoes and left shoes, as indicated by the legends in Fig. 1, and the racking of the shoes in the two lower shelf structures is the same as that 45 described with respect to the uppermost ones. The arrangement allows an operator to set up his machine for all the twelve pairs of shoes, or whatever the capacity of the rack, and to then take the shoes for operation 50 without shifting around and selecting first a right shoe and then a left, in accordance with the present time consuming practice with existing shoe racks. The operators by knowing that all of the right shoes are 55 together on certain shelves, and all the lefts are together on the next adjacent shelves, while the shoes of each pair are in vertical alinement one above the other, can rapidly perform the operations on the shoes, removing 60 and replacing the same in their proper positions in the rack, without delay or confusion and with the assurance of maintaining the shoes together in pairs.

By the design, construction and mounting 65 of the shoe supporting paddles to obtain the

above described racking and relative arrangement of the shoes, a further important feature and result of the invention is secured. The paddles 27-28 are of a minimum width and spacing to receive and support the shoes 70 therebetween with adjacent shoes out of contact, and the end paddles 28 are reduced in width to that necessary for supporting the side of a single shoe, so that the length of each shelf structure and resulting length of 75 the rack is reduced to the very minimum. This gives a saving in rack length and with the large number of racks required by a factory, obtains a material saving in valuable factory space.

A rack of the invention not only is designed and adapted for receiving and transporting unfinished shoes, but is also capable of ready conversion for receiving and holding finished shoes. Referring to the lower- 80 most shelf structure of Figs. 1 and 4, to convert the same for finished shoes, the toe rest 35 is moved to position across the paddles 27-28, forward of and against the vertical rods 35, and a cover of cloth or other soft, 85 non-marring material 40 is then placed over and covering the paddles and rest 35. Finished shoes, as L and R, can then be placed thereon sole downward and heel outward and forward of rest 35, with this rest extending under the instep of the shoes and by engaging the heels maintain the shoes in 90 position. Shoes so mounted on the rack are maintained against displacement from the ends of the shelf structure by the protecting 95 and guarding vertical rods 35. The rack is in effect an all-purpose structure and eliminates the requirement of different types of 100 racks for handling the finished shoes.

The design of the metal main frame of 105 the rack is such that a minimum of metal and weight is called for, yet the high strength and durability required of these racks is embodied therein. The metal parts of the frame are so positioned, to the rear 110 of paddles and shoes thereon, with respect to the wood and shoe contacting parts of the rack that the possibility of shoes striking the metal and being damaged thereby is eliminated, yet the metal frame is located to 115 receive and absorb the blows and shocks of collision or contact with structures adjacent the rack, and to thereby protect the wooden portions of the rack from damage. The metal frame base is of such dimensions as to permit of locating the paddles thereabove 120 but within the area defined thereby, and is constructed to provide a support for articles which it may be desired to carry with the 125 rack. The paddle mounting is such that a high factor of safety against breakage or failure is inherent in the structure and enables these paddles to bear large weights and receive hard blows without breakage, thus 130

eliminating the considerable expense of repair and maintenance for these racks.

It is also evident that various changes, modifications, substitutions, eliminations, and variations might be resorted to without departing from the spirit and scope of my invention, and hence I do not wish to limit myself to the exact and specific disclosures hereof.

What I claim is:

- 10 1. In a shoe rack, a shoe supporting shelf structure, embodying a series of spaced substantially horizontally disposed paddles for supporting and receiving shoes therebetween sole upward with adjacent shoes out of contact, each of said paddles formed with one longitudinal edge concaved and its opposite edge substantially straight, whereby spaces are formed between the adjacent straight edge of one paddle and concaved edge of the opposite paddle to receive and conform to only either right shoes or left shoes.
- 15 2. In a shoe rack, the combination of substantially horizontal disposed vertically spaced shoe supporting shelf structures each embodying a series of substantially horizontally disposed and spaced paddles for supporting shoes thereon and therebetween sole upward with adjacent shoes out of contact, the supporting paddles of one shelf structure each having a longitudinal edge concaved and the opposite edge substantially straight to form a space therebetween conforming to and receiving only right shoes supported on said paddles, and the supporting paddles of the adjacent shelf structure vertically aligned with said other shelf structure paddles and each having the opposite longitudinal edge concaved opposite to that of the paddles in the adjacent shelf structure, so as to receive and conform to only left shoes, the arrangement being such that shoes are racked on said adjacent shelf structures in vertically aligned pairs.
- 20 3. In a shoe rack, a metal frame including vertically disposed and spaced frame members formed of angle irons, bracket members secured to said end members extending substantially transversely thereof and horizontally from one side thereof, said brackets vertically spaced on the end members and the brackets of one end member in horizontal alignment with those of the opposite end member, a paddle supporting bar secured across and between each pair of aligned bracket members, and shoe supporting paddles secured at their inner ends to and at spaced intervals along each paddle bar, with said paddles extending substantially horizontally and outwardly from said bar.
- 25 4. In a shoe rack vertically disposed opposite end frame members each comprising a metal angle bar, a bracket member comprising an angle bar secured by its vertical

flange to each of said frame end members extending outwardly and substantially horizontally therefrom with its horizontal flange extending inwardly from said end member, the said bracket members mounted on said end members in horizontal alignment, a paddle supporting bar extending across and between said bracket members and secured at the under sides of the horizontal flanges of said bracket members, a series of spaced shoe supporting paddles secured at spaced intervals to and along said paddle bar and extending outwardly therefrom, and the end paddles secured to and received in said bracket members.

5. In a shoe rack, a frame including vertically disposed and spaced end members, vertically spaced horizontally disposed shelf structures extending between and supported by said frame end members, each shelf structure including a series of horizontally disposed and spaced shoe supporting paddles extending outwardly from said end members, and vertically disposed rods extending through and connecting the end shoe supporting paddles of each shelf structure.

6. In a shoe rack, spaced vertically disposed frame end members, horizontally disposed and vertically spaced shelf structures extending between and supported on said end posts, each shelf structure including a series of horizontally disposed spaced shoe supporting paddles, a rod vertically disposed and extending transversely through the vertically aligned end paddles of the shelf structures adjacent the outer ends of such paddles, and a movable toe rest mounted extending across the inner ends of the shoe supporting paddles of each shelf structure, and said toe rest movable to position across the outer ends of the paddles of each shelf structure, forwardly of and positioned by said end paddle connecting rods.

7. In a shoe rack, a frame including spaced vertically disposed end posts each formed of a metal angle bar, a bracket formed of a metal angle bolted by its vertical flange to a flange of each end post and disposed in substantially horizontal position extending outwardly therefrom, said brackets in horizontal alignment with their horizontal flanges disposed inwardly toward each other, a paddle bar bolted at its opposite ends to the under side of the horizontal flanges of said brackets between said end posts, a series of spaced shoe supporting paddles bolted at their inner ends along said paddle bar and extending outwardly therefrom in substantially horizontal position, and the opposite end paddles received in said brackets and mounted on the horizontal flanges thereof and secured at their inner ends to said brackets and the paddle bar by the paddle bar securing bolts.

8. In a shoe rack, a main frame of metal

embodying a substantially rectangular and horizontal base, with vertically disposed, spaced end members each comprising an angle bar secured to opposite ends of said base adjacent one side thereof, each of said end members having one flange of extended width and these flanges disposed parallel and extending toward the opposite side of said base, bracket members each comprising a metal angle bar secured to the parallel extended flanges of said end members, respectively, and extending substantially horizontally and outwardly from said end members, a paddle bar extending between the inner ends of said bracket members and bolted to the under side thereof, a series of shoe supporting paddles bolted at spaced intervals along said paddle bar, extending substantially horizontally and outwardly therefrom between said end members, and the opposite end shoe supporting paddles received in and secured to said bracket members.

9. In a shoe rack, a substantially rectangular base including opposite side and opposite end members, vertically disposed spaced end posts secured to said opposite end members of the base adjacent one of the base side members, each of said posts comprising a metal angle having one flange thereof wider than the other flange, the said posts secured to said base end members by said wider flange which extends therealong toward the opposite side member of the base, a bracket formed of a metal angle bolted by its vertical flange to the wider flange of each end post and disposed in substantially horizontal position extending outwardly therefrom with its horizontal flange lowermost, said brackets in horizontal alignment with their horizontal flanges disposed inwardly toward each other, a paddle bar bolted at its opposite ends to the under side of the horizontal flanges of said brackets between said end posts, a series of spaced shoe supporting paddles bolted at their inner ends along said paddle bar and extending outwardly therefrom in substantially horizontal position above and across said base but within the vertical confines thereof, and the opposite end paddles received in said brackets, respectively, and mounted on the upper side of the horizontal flanges thereof and secured at their inner ends to said brackets and the paddle bar by the paddle bar securing bolts.

Signed at Auburn, New York, this 10th day of May, 1928.

JOHN S. HOFFMIRE.
